TANK CLOSURE

John Nelson, Minneapolis, Minn., and Victor C. Norquist, Kansas City, Mo., assignors to Butler Manufacturing Company, Kansas City, Mo., a corporation of Missouri

Application January 28, 1933, Serial No. 654,006

5 Claims. (Cl. 220—44)

Our invention relates to tank closures and more particularly to a closure provided with a fire-proof vent, for tanks adapted to contain and transport inflammable liquids.

5 In transporting or storing inflammable liquids, it frequently happens that the lighter ends of a liquid will volatilize to form explosive or inflammable vapors. This vapor will escape from the tank due to the expansion occasioned by the heat 10 of the sun, or by the displacement of the vapor due to the filling of the tank.

It is known in the art to provide fire-proof screens to vent a tank to allow the escape of the vapors without the danger of fire. It frequently 15 happens, however, that a fire adjacent the tank, or an extremely hot sun will cause such a rapid volatilization of the liquid that the vapors will not escape rapidly enough. This is particularly true also when the tank is being filled. In other 20 words, the venting requirements necessary for a tank will vary depending upon certain factors. Normally, a small vent will suffice for all practical purposes. Occasions may arise where a larger vent will be needed.

25 One object of our invention is to provide a tank closure which will adapt itself to all venting requirements and at the same time be perfectly safe with respect to the fire hazard.

Another object of our invention is to provide 30 a tank vent which will allow for both expansion and contraction of the liquid and/or vapor within the tank, while maintaining fire-proof conditions.

A further object of our invention is to provide 35 a novel closure which will prevent the explosion of a tank in event of an adjacent fire by permitting the rapid venting of the volatilized liquid.

A still further object of our invention is to provide 40 a vent which will preclude the stress occasioned by temperature changes and the resulting expansion and contraction of the gas and/or liquid within the tank.

Further objects of our invention will appear 45 from the following description.

45 In the accompanying drawings which form part of the instant specification, and which are to be read in conjunction therewith and in which like reference numerals refer to like parts in the various views:

50 Fig. 1 is a plan view of our closure assembly.

Fig. 2 is a sectional view taken on the line 2—2, Fig. 1.

Fig. 3 is a sectional view taken on the line 3—3, Fig. 2.

Fig. 4 is a sectional view taken on the line 4—4, Fig. 2.

In general, our invention contemplates a large opening leading to the interior of the tank and separated therefrom by means of a plurality of foraminous screens. Inboard of the screens and blocking an opening leading to the interior of the tank, we provide our novel valve arrangement. The valve arrangement consists of a series of three valves. A large valve is adapted to lift to 10 expose the maximum opening of the tank. This opening will be sufficiently large to vent the tank in event the tank car or receptacle be subjected to the heat of a fire. Within the large valve we provide two valves, one adapted to lift in event 15 the pressure within the tank be decreased by a reduction of the temperature or by withdrawing liquid from the tank to relieve the partial vacuum which would be thus formed. We provide too another valve adapted to lift in event pressure 20 be created due to the expansion of the vapors and/or liquid within the tank due to an increase in the temperature and/or the filling of the tank.

More particularly, referring now to the drawings, a closure member 1 is secured to a large opening within the tank by riveting, welding or in any other suitable manner. The closure member is provided with an opening 2 which may be used as a filling or gauging opening. The closure member is also provided with a larger opening 30 defined by a coaming 3. The lower portion of the coaming terminates in a flange 4 and supports a plurality of screens 5. These screens may be of foraminous sheet material or of metal mesh. A plurality of pillars or posts 6 are supported by 35 the flange 4 and support a cover plate 7. The interior periphery of the flange 4 is provided with a packing ring 8 which forms the valve seat for a large valve 9. The valve 9 is provided with a central bore 10 which communicates with a pair of bores 11 and 12 running at right angles to the bore 10. The bores 11 and 12 are in communication with the atmosphere through the screens 5. The interior of the bore 10 is provided with a rabbet 13 in which is seated a packing ring 14. 40 This packing ring 14 forms a seat for a valve 15, as can readily be seen by reference to Figs. 2 and 4. The valve 15 is provided with a valve stem 16 which is slidably positioned in a valve stem guide 17. The upper portion of the valve 9 is provided with a bore 18. This bore 18 is provided with a rabbet 19 in which is seated a packing ring 20. 45 This packing ring forms the seat for a valve 21. The bore 18 is covered by a cover plate 22 which is held in place by screws 23, thus making it 50 55

gral with the valve 9. The interior of the cover plate 22 is provided with a socket 24 which acts as a guide for the valve stem 25 of the valve 21. The space in bore 18 above valve 21 is in communication with the interior of the tank by means of a pair of ducts or bores 26 and 27, as may readily be seen by reference to Fig. 2. Bore 18 communicates with an enlarged space 28 in which valve 15 is seated and into which bores or ducts 11 and 12 lead. The valve 9 is provided with a handle 29 so that the entire assembly may be lifted from the valve seat 8 after cover plate 7 is removed by removing nuts 30. This will give access to the interior of the tank for men when it is desired to inspect or clean the same. The entire assembly is protected by a hinged cover plate 31 which is pivoted to lugs 32 secured to closure member 1, as can readily be seen by reference to Figs. 1, 2 and 3. Pin 33 forms the pivot for the cover plate 31, which is provided with a lug 34. The lug 34 has an opening 35. The small opening 2 which may be used for a filling or gauging opening, is provided with a cover plate 36 hinged to the closure 1 by means of pin 37. The small cover plate 36 is provided with a hasp 38 which may be secured thereto in any suitable manner. The hasp 38 is adapted to fit over lug 34 so that a lock may be placed through opening 35 to secure both cover plate 31 and cover plate 36.

In operation, when the tank is being filled at a slow rate, or if pressure accumulates within the tank due to expansion, valve 15 will lift and the pressure released through ducts 11 and 12, through the screens 5 to the atmosphere. If the tank should be adjacent a fire or if it is being filled at an extremely rapid rate so that valve 15 is insufficient to take care of the accumulated pressure, large valve 9 will lift and vent the pressure to the atmosphere through screens 5. If a light vacuum should be built up due to contraction of the gases and air within the tank, this vacuum will communicate with bores 26 and 27 to the top of valve 21, which will lift and permit the reduced pressure to be equalized by the passage of air from the atmosphere through screens 5, through ducts 11 and 12 to the space 28 above valve 15 and into the tank. It will be observed that the passage of vapors out of the tank or of air into the tank is always through screens 5, so that there is no danger of fire.

It will be appreciated that we have accomplished the objects of our invention. We have provided a novel tank closure which will vent under different venting requirements from the slightest to the most severe. Our tank closure renders a tank practically immune from fire or explosion due to the fact that any sudden or large increase in pressure may be vented by means of the large valve 9. The valves 21 and 15 will take care of the usual variations in pressure due to expansion and contraction and/or the filling or withdrawal of liquid from the tank.

It will be understood that certain features and subcombinations are of utility and may be employed without reference to other features and sub-combinations. This is contemplated by and is within the scope of our claims. It is further obvious that various changes may be made in details within the scope of our claims without departing from the spirit of our invention. It is, therefore, to be understood that our invention is not to be limited to the specific details shown and described.

Special attention is invited to valves 15 and 9. Valve 15 is somewhat lighter per unit of area than is valve 9. It will be noted that this will permit valve 15 to operate first to take care of all normal expansion in the tank, while valve 9 will only operate when the expansion is abnormal or too rapid to be taken care of by valve 15, which, being heavier per unit of area, will remain stationary while valve 15 operates.

Having thus described our invention, what we claim is:

1. A closure for a tank comprising a plate having an opening, a first valve seated in said opening, said first valve being provided with two ducts connecting the tank inside with the atmosphere, a second valve seated in said first valve and controlling one of said ducts, and a third valve seated in said first valve and controlling the other of said ducts.

2. A closure for a tank comprising a plate having an opening, a valve having two bores seated in said opening and adapted to lift to release pressure within the tank, an auxiliary valve seated in one of said bores in the valve adapted to lift to release pressure within the tank, and a supplementary valve seated in the other of said bores in the valve adapted to lift to release a partial vacuum within the tank.

3. A closure for a tank having an opening including in combination a first valve seated to close said opening, said valve being formed with two ducts providing communication between the tank interior and the atmosphere, a second valve seated in said first valve and controlling one of said ducts, and a third valve seated in said first valve and controlling the other of said ducts.

4. A closure assembly for a tank opening including in combination a valve formed with two passages and a pair of auxiliary valves controlling said passages, the construction being such that the assembly is adapted to lift to release pressure in the tank, one of said auxiliary valves is adapted to relieve pressure in said tank and the other of said auxiliary valves is adapted to release a partial vacuum in the tank.

5. A closure as in claim 3 wherein foraminous material is disposed adjacent the first valve to extend across the communication between the tank interior and the atmosphere.

JOHN NELSON.
VICTOR C. NORQUIST.
